COMPUTING MACHINE

Burnham C. Stickney, Hillside, N. J., assignor to
 Underwood Elliott Fisher Company, New York,
 N. Y., a corporation of Delaware

Application August 29, 1933, Serial No. 687,273

38 Claims. (Cl. 235—60)

This invention relates to adding machines of the ten-key type, in which the keys set up indexing devices, after which the types are set accordingly by means of a general operator, and the printing of the desired number is effected. Machines of this type are illustrated in the United States patents to Oscar J. Sundstrand, Nos. 1,198,487 and 1,583,102 issued on September 19, 1916 and May 4, 1926 respectively.

10 In machines of this type, it is usual to index the zero-type as well as the digit-types, so that it is necessary to strike the zero-key once for every zero that is to be printed.

It is an object of this invention to provide 15 means for eliminating most of the labor which is usually connected with the setting of the zero-indexing pins.

Customarily a machine of this style is provided with nine type-bars, each of which carries nine 20 digit-types and a zero-type. The zero-types are usually normally in position for printing in the machine illustrated in the above-mentioned Sundstrand patent. The work of the usual zero-key, therefore, is to index the type-bars and to 25 feed the indexing-carriage a step. In the Sundstrand machine, this carriage is shifted to the extent of one denomination at each key-stroke. In the machine illustrated in the patent aforesaid, if the amount of, say, 5,000,000 is to be added, 30 the operator first strikes the digit-key "5" once, and then depresses the "0" key six times.

According to one feature of the present invention, the time and number of operations required to index a plurality of successive zeros 35 is materially reduced by providing an auxiliary set of zero-keys. By striking the first auxiliary key, two zeros are automatically indexed accompanied by two steps of the indexing-carriage. By striking the second auxiliary key, three zeros 40 are indexed, and three steps of the indexing carriage effected. By striking the third auxiliary key, three zeros are concomitantly indexed, with a corresponding movement of the indexing-carriage; and by striking the fourth auxiliary key, four zeros are concomitantly indexed and the 45 carriage stepped accordingly.

These multiple-zero keys are connected to a source of power, and cause the same to actuate a zero-key train as many times as there are zeros represented by the selected key. For example, if the auxiliary key bearing four zeros is depressed, the source of power will impart to the zero-key train four successive impulses, thus setting up four successive zero-pins in four denominations, just the same as if the old single zero-key had been struck four times.

The zero-key train is operated by means of an oscillator, which is driven by a power-driven escapement-wheel. The wheel vibrates an anchor-escapement, and operates the zero-train repeatedly in one direction. The zero-train is returned to normal position by a restoring spring.

This escapement-wheel is fixed upon a spring-driven power shaft, and the restoring spring is 10 rewound by the general operator of the adding machine.

The extent to which the power shaft escapes, is controlled by the four novel auxiliary keys. Upon the shaft is fixed a universal feed-wheel, 15 which is normally restrained by a pawl. The depression of any one of the auxiliary keys will release the pawl from the feed-wheel, and at the same time, will control an individual dog, whereby the extent of rotation of the released 20 power-shaft is limited. If, for example, the "0000" key is depressed, the power-shaft is permitted to escape four teeth, thereby causing four successive oscillations of the escapement anchor or lever, and the setting of four zero index-pins, 25 one in each of four successive denominations. Upon the return of the depressed key, the individual dog is withdrawn from its control of the shaft, and the original pawl is reengaged to restrain the shaft against further revolution.

If it is desired to print six zeros, it is only necessary to operate the "000" key twice in succession. Seven zeros are provided by depressing first the "000" key and then the "0000" key. For indexing eight zeros, the "0000" key may be depressed twice. From the above it is apparent that considerable time may be saved by using the present invention.

With these and incidental objects in view, the invention consists in certain novel features of 40 construction and combinations of parts, the essential elements of which are set forth in appended claims, and a preferred form of embodiment such as hereinafter described with reference to the drawings which accompany and form 45 part of the specification.

In said drawings:

Figure 1 is a sectional side elevation of a Sundstrand adding machine, with which the present improvements have been incorporated; the parts 50 being shown in normal positions.

Figure 2 is a sectional plan of the same, parts being omitted.

Figure 3 is a detail view in sectional elevation, of the power-driven zeroizing mechanism, show- 55

ing one of the novel multiple-zero keys; all parts being in normal positions.

Figure 4 is an enlarged detail view, showing the position of the anchor-escapement when oscillated in one direction by the impulse-wheel 76, and having operated the zero-indexing train and carriage-feeding train 53 accordingly.

Figure 5 is a front elevation of the zero keys and power-shaft, and their connections, the parts 10 being in normal position.

Figure 6 is a perspective, showing the "5" zero-key 87 in depressed position with its dog 89 engaged with ratchet-wheel 90, the shaft 75 having been rotated five teeth, whereby five zero index-pins have been set up.

The Sundstrand machine comprises a platen 2 (Fig. 1) and type-bars 3, each provided with ten types to print from "zero" to "9." The uppermost type prints "0", the next lower "1", and so on. 20 The type bars 3, in the machine illustrated in Sundstrand, 1,583,102 above referred to, are normally in position to print ciphers. To lift each type bar 3 from the cipher-printing position to any other selected position there is used in said 25 machine a rear lift-arm 10 which carries a roller that lies in a notch 11 in the type-bar, the arms 10 being journaled on a fixed shaft. Rigid with each arm is another arm (not herein shown, but indicated at 13 in the Sundstrand patent referred 30 to), which arm is yieldingly connected through springs to two side members. A main rock-shaft 26, (Fig. 1), rocked by a handle 27 is connected with said side members. When the operator pulls the handle forwardly, movement is yieldingly transmitted through the springs to such of the type bars 3 as are free to rise. When the operator releases the handle 27 on the completion of the forward stroke, means of suitable character returns the handle to normal position. The 35 means for restoring those bars 3 which were raised in the forward stroke of the handle, includes restoring levers, which during the return stroke of the handle, are rocked in a direction to restore the type bars 3 to their initial (lower) positions, all as fully shown and explained in the Sundstrand Patent 1,583,102 heretofore referred to.

The means for limiting the extent to which the bars 3 may rise and thus to determine which 50 numerals shall be brought to the printing position, comprises a group of settable indexing-stops 42 arranged in vertical columns, each indexing-stop being horizontally slideable back and forth in a stationary guide-frame 43. When moved rearwardly from normal position the stops are projected in the paths of movement of devices carried by the type bars 3 to differentially limit the upward movement of the type bars. These devices comprise angular arms 45 vertically hinged 55 to the lower portions of the several type bars 3, and vertical arresting pins 46 having openings at their lower ends through which the forward ends of the arms 45 extend. The arresting pins 46 arranged in a transverse row, are guided for vertical movements in a step-by-step shifting carriage or slide 47 which is mounted on, and travels along, a stationary transverse guide rod or track 48. The track 48 is so positioned with respect to the indexing stop guide-frame 43, that the carriage 47 is shiftable to carry the vertical arresting pins 46 from their normal or initial position at the left-hand side of the group of stops 47 into vertical alignment with the successive columns of stops.

75 Those type bars 3 which are not needed in ac-

cumulating or printing a given item, are prevented from rising when the handle is pulled forward, by a detent-plate 48a, (Fig. 2), guided to move in a horizontal plane, and more fully disclosed in the Sundstrand patents above-named. 5

The means for projecting the indexing stops 42 into the vertical path of movement of the type bar arresting pins 46 includes a plurality of digit-keys 49, (Figs. 1 and 2), conveniently numbered from "1" to "9", and a "0" key 49a. The stems 10 50 of the keys are mounted for vertical movement in guide-frames 51 located at the forward end of a base 40 of the machine. Each key is arranged to tilt a bell-crank 52 pivoted at its opposite ends in the side walls of the frame 51. The 15 transversely extended head of each of the bell-crank levers associated with the keys 49, 49a bears against the shouldered front end of individual links 53, the rear ends of which are pivoted to the arms of corresponding horizontal levers 54 20 pivoted on a vertical axis 55. Springs 56 connected to the arms 57 of the last-mentioned levers serve to restore the corresponding keys to normal positions after operation. A multiple-armed, universal lever 58, pivoted on the axis 55, has an arm 25 58a to which is fixed a depending vertical universal bar 59. A spring 61 connected to another arm of the universal lever, normally holds the universal rod 59 in contact with the arms 54a which are rigid with the respective key levers 54. 30

The indexing-mechanism also includes a shiftable bracket 62, which is pivoted at 63 to shift denominationally step by step, in clockwise direction and return. The bracket 62, at its rear end, carries a post 64 in which are slidably supported 35 the rear ends of push-rods 65. The forward end of each indexing-push rod 65 is pivoted to an arm of its associated key lever 54. The key levers 54 correspond to the keys "0" to "9", inclusive. There is no need of providing a push-rod 65 for 40 the key "9." An additional escapement-tripping push-rod 65a is pivoted to the universal lever 58. The push-rods 65 and 65a are arranged in a vertical column and all except the uppermost or escapement-tripping push-rod 65a, are adapted 45 to push the indexing-stops 42 rearwardly out of normal position and into the path of the upwardly-settable type-bar arresting pins 46. The escapement-tripping push-rod 65a is used only for escapement purposes. 50

The carriage 47 is caused to shift in unison with the bracket 62 by means of a pin 66 fixed to the bracket and lying within a fork 67 on the carriage.

As the operator sets up an item on the keyboard by successively depressing the appropriate keys, the carriage 47 and the bracket 62 are moved from one vertical row of indexing-stops 42 to the next row as each number-key is depressed and released. The series of push-rods 60 65 normally stands in front of the vertical column of index-stops 42 which is farthest to the left, and is stepped to the successive vertical columns of index-stops as the setting up of the item progresses. The series of arresting pins 46 65 is moved from left to right, step by step (one step for each denomination in the item being set up), thereby bringing the necessary number of pins 46 into vertical alignment with the index-stops 42 that have been set by the push-rods 65. 70

The carriage 47 and the bracket 62 are moved to the right by a spring 68, controlled by an escapement. The escapement includes the uppermost push-rod 65a, and a tooth 64a formed on the upper end of the vertical post 64 projecting 75

upwardly from the rear end of the bracket, in combination with a curved ratchet bar or rack 69 pivoted to the framework at 10. The ratchet-bar is yieldingly held against the topmost push-rod 65^a or the tooth 64^a by a spring 71.

The universal bar 59, depends from the uppermost or universal lever 58, and hence, the uppermost or escapement-controlling push-rod 65^a will be moved whenever any one of the zero or digit 10 keys 49^a, 49 is depressed.

When the escapement-controlling push-rod 65^a, upon depression of a key, pushes a tooth of the ratchet-bar 69 clear of the tooth 64^a of the post 64, the spring 68 pulls the carriage 47 and the bracket 62, together with the row of push-rods, to the right, until the rearwardly projected end of the push-rod 65^a contacts with and stops against that tooth of the ratchet-bar just released from the tooth 64^a of the post 64, and the tooth 64^a is resting on the flank of the succeeding right hand tooth.

When the operator lifts his finger from the depressed key 49, the escapement-controlling push-rod 65^a is withdrawn by its spring 61 from engagement with the ratchet-bar tooth, and the spring 68 pulls the carriage 47 and the bracket 62 slightly farther to the right until the tooth 64^a of the post 64 stops against the said next tooth of the ratchet-bar with which it is alined. The carriage 47 and bracket 62 remain in their advanced positions after setting up an item, until the handle, near the end of its return stroke, operates means (not shown) to restore the carriage 47 and the bracket 62 to the left into their initial positions.

With the carriage 47 and bracket 62 in their normal positions, depression of any digit-key 49 (or the zero-key 49^a), swings a bell-crank 52, which, by means of its link 53, rocks a corresponding rear lever 54 to thrust rearwardly an individual push-rod 65, for projecting a corresponding index-pin 42 in the left-hand tier at Figure 2. The set of push-rods 65 then shifts to the next tier of index-pins 42, as above explained.

As mentioned above, the stepping movement of the pivoted bracket 62 is imparted to the carriage 47, which takes one step for every key-stroke. This determines the denominations of the integers in the amount printed upon the work-sheet on the platen. The first step of the carriage 47 brings the right-hand type-bar 3 under the control of the set index-pin 42. The second complete step of the carriage brings the first two right-hand type-bars 3 under the control of the first two left-hand set index-stops, and so on.

In Figures 1 and 3, it is also seen that the usual zero-key 49^a controls the printing of zeros, having an indexing and letter-space feeding train, including a bell-crank 52, a link 53, a key-lever 54, 60 a push-rod 65, and an indexing stop 42. There is one zero-indexing stop at the bottom of every tier or column of indexing stops, making nine indexing stops for zeros, or one in each denomination. These zero stops, since they are at the bottom, intercept the arresting pins 46 and their respective type bars 3 and thereby prevent the type-bars from rising, so that the usual hammers 180, Figure 1, strike the uppermost or zero types on the type-bars and drive them against 70 the work-sheet on the platen 2.

As so far described, the operation is old and well known, and is set forth in detail in various Sundstrand patents, including those above mentioned. In said patents there is a normally restrained hammer 180 for each denomination.

These hammers are not released for action unless they come into the indexing-range, the ones so affected being released upon operation of the general operator 21. Hence no zero will be printed at the left hand of the amount which has been 5 set up in the machine. This result is effected by the provision of the detent plate 48^a.

The type-bars 3 have racks (Fig. 1) which operate adding-wheels 125.

The carriage 47 is usually provided with an index pointer or finger, 12, (Fig. 2) to co-operate with a scale 73 upon the machine-frame, to show how many denominations have been indexed.

From the foregoing, it will be seen that, for every operation of the zero-key 49^a, the indexing-mechanism is set for causing a cipher to be printed in the corresponding denomination of the amount.

In the illustrated form of this invention, the particular indexing-train which is operable by 20 the zero-key 49^a, is also mechanically operable repeatedly and successively by mechanical means independently of said zero-key 49^a, and independently of its stem 50; said key 49^a preferably remaining stationary during the novel mechanical 25 operation now to be described.

To this end, a zeroizing spring 74 (Fig. 6) powers a shaft 75, upon which is fixed an escapement-wheel 76 to give impulses to opposite pallets 77, 78, of an anchor-escapement, which is pivotally mounted at 79; the rotation of the wheel 76 causing the escapement to oscillate. Said anchor-escapement strikes an abutment 80 upon the front end of the lowermost link 53 (which forms part of the aforesaid zero-indexing train). 35 Hence said zero-link 53, together with its train, is mechanically operated repeatedly, so long as the shaft 75 rotates; and, at every operation of said train, a lowermost index-pin 42 is set, and the crane 62 and carriage 47 are also stepped 40 along. In this way, the machine is indexed for zero in as many denominations as there are complete oscillations of the pallet-lever 77, 78.

Normally, the power-shaft 75 is restrained by a locking dog 81, which is pressed by a spring 45 83 into engagement with a ratchet-wheel 82, fixed upon said power-shaft 75. This dog 81 may be released by any one of four auxiliary zero-keys, numbered 84, 85, 86, and 87, which are placed at the front of the keyboard, two at each side of 50 the zero-key 49^a, as at Figure 6. Said multiple-zero-indexing keys 84 to 87 are mounted upon stems 88. For the purposes of this disclosure the stems 88 of the keys 85 and 87 may carry forwardly extending detents 89, and it is to be understood that the stems of the special keys 84 and 86 are similarly equipped. When one of these keys is depressed, its detent 89 engages the teeth of a ratchet-wheel 90, individual thereto, and loosely mounted on the power-shaft 75, as herein-after explained, in such a manner as to prevent the ratchet-wheel from being rotated by its tensioned spring 91, one end of which is fastened to the power-shaft 75, around which it is coiled in a direction reversely to the direction in which the shaft is turned during the operation of setting a plurality of zeros successively in the machine. 65

The opposite ends of the coiled springs 91 are 70 secured to their respective stop-ratchets 90 in any convenient manner.

The hub 97 of each of the respective ratchet wheels 90 carries a longitudinally projecting arcuate lug 98, the lugs being of progressively less ar- 75

cuate extent as the number of complete oscillations required of the anchor escapement.

In the form illustrated, the individual coil springs 91 of the several ratchet wheels 90, normally hold the rear faces of the lugs 96 against associated stop teeth 95, one for each ratchet wheel, as shown at the left, in Fig. 6. The stop teeth arranged at intervals along the power shaft 75, are fast with and project radially therefrom. The differential ratchet wheels 90, and the impulse wheels 76 preferably have the same number of teeth.

The springs 91 are respectively inferior to the motor spring 74.

When any auxiliary key (as shown at 87, Figure 6) is depressed, a key-pin 92 depresses an arm 93 upon a universal shaft 94, which carries the locking dog 81, to withdraw the locking dog from escapement-wheel 82, and permit the power-shaft 75 to drive the impulse-wheel 76, to oscillate the anchor-escapement 77, 78, and repeatedly operate the zero-indexing train.

During this operation, the key 87 is held down, with its detent 88 engaged with its own ratchet-wheel 90 to hold the latter stationary. The power-shaft 75, therefore, continues to revolve until the tooth 95 thereon associated with the lug 96 on the hub 97 of the ratchet-wheel 90 appropriate to the key 87, is arrested by contact with the front face of its lug 96 as shown at the right in Figure 6. The notch 98 formed in the hub 97 is sufficiently extensive to permit rotation of the power-shaft 75 relatively to the ratchet 90 of special key 87, to the extent of five notches of the impulse-wheel 76. Thus, when an auxiliary key 84 to 87 is depressed, the power-shaft 75 is released to the action of its power-spring 74 and drives the impulse-wheel 76, oscillating the anchor 77, 78, and repeatedly thrusting rearwardly the lowermost indexing-train 53, 54, 65, as viewed in Fig. 1. This will interpose zero stops 42 of corresponding denominations into the paths of the arresting pins 46 to prevent the selected type-bars 3 from rising and presenting any digit-type in front of the platen, wherefore these type-bars will be caused to print an array of zeros. The return swing of the anchor 77, 78, is aided by the lever-restoring spring 56 (Fig. 2).

It will be seen that the lengths or extents of the notches 98 vary in the different hubs 97, in correspondence with the number of ciphers which are indicated upon the corresponding key although only two hubs 97 are disclosed in the drawings, it will be understood that one such hub 55 is associated with each of keys 84, 85, 86, and 87.

It is contemplated that the hub 97, with which the key 84 is intended to coat, will be formed with a notch 98 of such radial length as will permit of two steps of movement of shaft 75.

A hub 97 associated with the key 85 is formed with a notch 98 permitting three steps of movement of shaft 75.

Although no hub is shown in connection with the disclosure of key 86, it will be understood that such a hub identical in all respects with those shown in Figure 1, excepting that a notch permitting of four steps of movement of shaft 75, will be employed.

Key 87 coats with a hub 97 formed with a notch of such radial length as will permit of five steps of movement of the shaft 75. Thus it will be seen that depression of any auxiliary key releases the power-shaft 75 to operate the zero-indexing train in one direction, the train, on its 75 return under the influence of springs 56 and 61,

operating to rock the escapement anchor back to its normal position assisted by appropriate camming action of the teeth of wheel 76. If more than five zeros are to be printed, in one line, the extra zeros may be provided by subsequently depressing key 49^a or the desired auxiliary or special key.

At the completion of the zero-indexing, the spring 74 is pressing the appropriate stop tooth 95 against the forward face of its lug 96, which 10 is restrained by the dog 81 of the associated key depressed. At this time, the pallet or anchor 77, 78 is in normal position, and the zero-indexing train 53, 54 and 65 is also in normal position.

When the selected auxiliary key is released 15 from pressure, the spring 88, (Figs. 1, 5, and 6), restores it to normal position, thereby withdrawing the tripping pin 92 from contact with the arm 93 on the tripping shaft 94. Co-incidently with the release of the arm 93 by the tripping pin 92, 20 the spring 88, (Fig. 6), snaps the locking dog 81 into engagement with the locking latch 82 to prevent farther clockwise rotation of the power-shaft 75, and the consequent setting of additional 25 undesired zero stops 42.

Meanwhile, the key-restoring spring 88 elevates the key stem 88 to withdraw the detent 88 from engagement with the differential ratchet 90.

The power-shaft 75, in its clockwise rotation, has tensioned the coil spring 91 appertaining to 30 the particular ratchet wheel 90 engaged by the detent 88 of the depressed multiple zero key, so that upon release of the ratchet wheel 90 by its detent 88, the tensioned coil spring 91 rotates in clockwise direction the ratchet 90 with its hub 97 35 and lug 96, until the rearwardly facing wall of the lug 96 contacts and is arrested by the front face of the radially extending stop tooth 95 of the power-shaft.

Obviously, the angular position of the power-shaft 75 and stop tooth 95, at this point in the operation of the machine, differs from the angular position occupied at the start of the operation, due to the fact that the power-shaft 75 has advanced in clockwise direction a distance equal 45 to the distance between the front and rear faces of the lug 96.

Also the ratchet wheels 90 with their hubs 97 and lugs 96 corresponding with the undepressed multiple zero keys, turn idly with the power-shaft 75 on its advance by the motor spring 74, the coil springs 91 serving as a connecting means between the idle ratchet wheels and the power-shaft.

During the operation of the keys for setting up 55 the rest of the same amount, either the zero-key 49^a or any of the auxiliary keys 84 to 87 may be operated to introduce one or more zeros in the amount wherever necessary.

Thus, the introduction of zeros can be accomplished without the necessity of counting the number of times the zero key is depressed, and without the necessity of operating the key 49^a repeatedly. Also labor is saved, time is gained and 60 liability of errors is avoided.

Retensioning of the motor spring 74 and return of the power-shaft 75 and parts carried thereby to their normal positions after each printing operation, are effected by the handle or general operator 27, (Figs. 1, 2, and 5), which 70 is connected by a link 100, (see Fig. 6) to a re-winding crank 101. The crank has a wrist 102 in a slot 103 in the forward end of the link, and at its opposite end, the crank is formed into a toothed segment 104 in constant mesh with a 75

pinion 105 fast on the right hand end of the powershaft 75.

During the advance of the power-shaft 75, under the influence of the spring or motor 74, the pinion 105 rocks the restoring segment 104 to cause the wrist 102 to travel towards the rear end of the slot 103 in the restoring link 100. At the concluding portion of the initial or forward stroke of the general operator 27, the crank 101 is rocked, causing the segment 104 to reversely rotate the power-shaft 75 by means of the pinion 105, to rewind the spring 74. The locking dog 81 rides idly over the teeth of ratchet-wheel 82 during this operation.

15 During such reverse rotation of the power-shaft 75, it is not desired that the impulse or escapement wheel 76 rotate, and therefore, such impulse wheel is connected by a pawl or yielding clutch 106 to the power-shaft, said clutch having 20 a restoring spring 107 and ratchet-teeth 108 to engage similar teeth upon the hub 109 of the power-escapement wheel 76 which is restrained from backward movement by a suitably pivoted back-check pawl 110, (Figs. 3 and 4), held effective in one direction by a spring 111.

A spring 112 operates through the bell-crank 52 to hold up the usual zero-key 49^a during the operation of the auxiliary zero-keys. The auxiliary key-stems 88 are held in the upper guide 30 plate 51 and also in lower eyes 113, (Figs. 1 and 2.)

The described novel power and trip shafts 75 and 94 are journaled in side brackets 114, secured upon the main framework, and the anchor-escapement is supported upon a bracket 115, Figure 3, all enclosed by a cover-plate 116, (Fig. 1), at the front of the machine.

In a machine having the capacity of that herein illustrated, the power-shaft 75 need not be 40 capable of rotating beyond the distance required for setting up nine zero index-pin stops, and the advance movement of the segment 104, and consequently of the power-shaft, may be limited by a stop 117, Figures 1 and 6.

45 It is also observed that for a stop-setting stroke of the train there is required more power than for the return stroke thereof, and the teeth of the pallets and of the impulse-wheel may be shaped accordingly, so that the power-shaft may 50 move through a greater angle when advancing the stop-setting train than when returning it. The impulse-wheel 76, through the anchor 77, 78, may exert a good leverage upon the train, to drive it through its initial stroke, and to tension its returning spring 61, while it has much less leverage upon the train for effecting the return stroke thereof; the movement, however, being aided by said returning spring 61, whereby the power of the drive-spring 74 is economized, 55 permitting the use of a spring of moderate strength, whose retensioning will not require undue labor to be applied to the general-operator handle 27.

Variations may be resorted to within the scope 60 of the invention, and portions of the improvements may be used without others.

Having thus described my invention, I claim:

1. In an adding machine having type and a step-by-step shifting denominational member 70 therefor, the combination of a spring-driven shaft, an impulse-wheel, an anchor-escapement caused by said wheel to oscillate under the power of said spring, a zero-type setting train repeatedly operable by said escapement, said train including a denominational shifting member,

whereby the machine is indexed for the printing of as many zeros as there are oscillations of the escapement-member, a ratchet on the shaft; and a dog engageable with the ratchet to restrain the shaft, a plurality of keys, each having means to release said dog, ratchet-wheels upon said shaft individual to said keys, detents operable by the keys to restrain the individual ratchet-wheels, and means yieldably connecting said ratchet-wheels to said shaft, to permit respectively different extents of rotation of the shaft, the spring-driven shaft continuing to rotate until a tooth thereon is arrested by a stop provided upon the selected ratchet-wheel.

2. In an adding machine having type and a step-by-step shifting denominational member therefor, the combination of a spring-driven shaft, an impulse-wheel, an anchor-escapement caused by said wheel to oscillate under the power of said spring, a zero-typesetting train repeatedly operable by said escapement, said train including a denominational shifting member, whereby the machine is indexed for the printing of as many zeros as there are oscillations of the escapement-member, a ratch on the shaft; and a 15 dog engageable with the ratchet to restrain the shaft; a plurality of keys, each having means to release said dog, ratchet-wheels upon said shaft individual to said keys, detents operable by the keys to restrain the individual ratchet-wheels, and means yieldably connecting said ratchet-wheels to said shaft, to permit respectively different extents of rotation of the shaft, said individual ratchet-wheels having hubs provided with notches or openings of graduated lengths, and 20 said shaft having teeth playing in said notches for variably limiting the rotation of the spring-driven shaft, the length or capacity of the notches in the hubs varying in correspondence with the number of zeros which are indicated 25 upon the corresponding keys.

3. The combination with zero indexing devices and an indexing train to set the zero indexing devices; of a multiple zero indexing key; and mechanism, rendered effective by a single operation thereof, to actuate the indexing train repeatedly and set a succession of the zero indexing devices.

4. The combination with zero indexing devices; and an indexing train therefor; of a plurality of 50 multiple zero indexing keys; power-operated means, rendered effective by a single operation of any one of said keys, to actuate the indexing train repeatedly to set a succession of the zero indexing devices; and differential mechanisms 55 controlled by each of said keys to arrest the power-operated means according to the number of zero indexing devices to be set by an operation of that key.

5. The combination with zero indexing devices; 60 a zero indexing key; and an indexing train controlled by said key for setting the zero indexing devices seriatim; of a plurality of auxiliary multiple-zero keys of different capacities; and means controlled by any of the auxiliary keys to effect, 65 at each single operation thereof, repeated operations of the indexing train in correspondence with the capacity of the key operated.

6. The combination with digit and zero indexing devices; digit and zero indexing trains to 70 index their respective devices; and an escapement to effect relative step by step movement between the indexing devices, and their indexing trains; of a multiple zero indexing key; and means, controlled by a single operation thereof, 75

to automatically actuate one of the indexing trains repeatedly to set the appropriate indexing devices in successive denominations.

7. The combination of zero indexing devices; 5 an indexing train therefor; an escapement to effect relative step by step movement between the indexing devices and the indexing train; a source of power connected to operate said escapement and indexing train repeatedly and thereby 10 set a plurality of zero indexing devices in succession; a control element, and means whereby a single operation of the element will determine the number of repeat operations to be made.

8. The combination with digit and zero indexing devices; separate indexing trains appropriate thereto; and an escapement to effect relative step by step movement between the indexing devices, and their respective indexing trains; of a source 15 of power actuated to operate one of said indexing trains repeatedly, to set a succession of indexing devices; a key; means controlled by the key to render effective the source of power; and means controlled by the key to predetermine the 20 number of impulses imparted by the source of power to the indexing train operated thereby.

9. The combination with digit and zero indexing devices; separate digit and zero indexing trains therefor; and an escapement to effect relative movement between the indexing devices 30 and their indexing trains; of a spring-actuated means connected to operate one of the indexing trains repeatedly, to set a succession of indexing devices; a key to trip the spring-actuated means for operation; means controlled by the key to 35 predetermine the number of operations of the indexing train by the spring-actuated means; and means to retension the spring incident to the operation of the machine.

10. The combination with digit and zero indexing devices; separate trains for setting the indexing devices of different values; and an escapement to effect relative movement between the indexing devices, and their indexing trains; of a motor-driven means to actuate one of the 40 indexing trains repeatedly; means to restrain the motor-driven means; a special key; and means controlled by the key to render the motor-driven means effective, and to predetermine the extent 45 of its repeated action upon the associated indexing train.

11. The combination with digit and zero indexing devices; separate indexing trains for setting the indexing devices of different values; and an escapement to effect relative movement between the indexing devices, and their indexing trains; of a spring-driven means to actuate one 50 of the indexing trains repeatedly; means to restrain the spring-driven means; a special key; means controlled by the key to release the restraining means, and to predetermine the number of successive impulses delivered by the spring-actuated means to the associated train; a general operator; and means connected therewith to restore the spring-driven means to normal, and to retension the spring.

12. The combination with a series of digit and zero indexing devices; manually operable setting trains appropriate thereto; and an escapement to effect relative movement between the series 55 of indexing devices and their respective indexing trains; of a motor-operated impulse wheel; an anchor escapement actuated by the impulse wheel and effective to operate one of the setting trains repeatedly; means normally restraining

said impulse wheel; and manually-controlled means to release the restraining means, and to control the number of train operations effected thereby.

13. The combination with digit and zero indexing devices; setting trains appropriate thereto; and an escapement to effect relative movement between the indexing devices and their respective setting trains; of a motor; a dog normally restraining the motor; manually operable 10 means to release the dog to free the motor for operation; and an impulse wheel operated by the motor, and so located with relation to one of the setting trains as to effect repeated operation thereof.

14. The combination with digit and zero indexing devices; setting trains appropriate thereto; and an escapement to effect relative movement between the indexing devices and their setting trains; of a motor; a dog to normally restrain 20 the motor from operation; manually operable means to release the dog; an impulse wheel operated by the motor, and so located relatively to one of the setting trains as to effect repeated operation thereof when driven by the motor in 25 one direction; and means rendered effective by the manually-operable means to arrest the impulse wheel after a predetermined number of strokes have been imparted to the setting train.

15. The combination with digit and zero indexing devices; setting trains appropriate thereto; and an escapement to effect relative movement between the indexing devices, and their setting trains; of a motor; a dog to normally restrain the motor; manually-operable means to 30 release the dog; an impulse wheel operated by the motor to effect repeated operation of a setting train; means rendered effective by the manually-operable means to arrest the impulse wheel after a predetermined plurality of operations of the setting train; and means to return the manually-operable means, restore the restraining dog to effective position and withdraw the arresting means from control of the impulse wheel.

16. The combination with zero indexing devices; a setting train therefor; and an escapement to effect relative movement between the indexing devices and the setting train; of a power-shaft; a restraining dog therefor; a plurality of multiple zero keys of different capacities; means operable by any of the multiple zero keys to release the dog and free the power-shaft for operation; an impulse wheel operated by the power-shaft, to repeatedly actuate the setting train, upon a single depression of the selected 55 multiple zero key; means rendered effective by the respective multiple zero keys to arrest the power-shaft differentially; and means to restore the depressed key to normal, disable the differential power-shaft arresting means and free the shaft-restraining dog for effective operation.

17. The combination with digit and zero indexing devices; setting trains appropriate thereto; a key associated with each train; an escapement to effect relative movement between the indexing devices and their setting trains; of a motor-actuated means to operate one of the setting trains independently of its associated key; an auxiliary key; and means rendered effective 65 thereby to control the repeated operation of the setting train by the motor-actuated means.

18. The combination with digit and zero indexing devices; setting trains appropriate thereto; and an escapement to effect relative move-

ment between the indexing devices, and their setting trains; of a motor-driven shaft; an impulse wheel; an anchor escapement oscillated by the impulse wheel, to repeatedly and successively 5 operate a setting train; and means to mechanically limit the number of such oscillations.

19. The combination with digit and zero indexing devices; setting trains therefor; and an escapement to effect relative movement between 10 the indexing devices and their setting trains; of a motor; a dog to normally restrain the motor; manually-operable means to release the dog; an impulse wheel operated by the motor; means associated with the impulse wheel to repeatedly 15 actuate a setting train; said train having a restoring spring to aid in returning the last-named means to normal; and means whereby a single operation of the manually-operable means will determine the number of repeat operations to be 20 made.

20. The combination with digit and zero indexing devices; setting trains therefor; and an escapement to effect relative movement between the indexing devices and their setting trains; of 25 a motor-driven shaft; means to normally restrain the motor-driven shaft; manually-operable means to release the restraining means; an impulse wheel operated by the shaft to repeatedly actuate a setting train; means controlled by the 30 manually-operable means to arrest the impulse wheel after a predetermined number of strokes of the setting train; a general operator; a link operated thereby; and a shaft-restoring means operable by the link to reversely rotate the shaft 35 to its starting position.

21. The combination with digit and zero indexing devices; setting trains therefor; and an escapement to effect relative movement between the indexing devices and their setting trains; of 40 a motor-driven shaft; a restraining means therefor; manually-operable means to release the restraining means; an impulse wheel operated by the shaft to repeatedly actuate a setting train; means controlled by the manually-operable 45 means to arrest the impulse wheel after a predetermined number of strokes of the setting train; a general operator; a link driven thereby; a shaft-restoring means operated by the link, said link having a slot thereon; and a wrist associated 50 with the shaft-restoring means and adapted to traverse the slot.

22. The combination with digit and zero indexing devices; setting trains therefor; and an escapement to effect relative movement between 55 the indexing devices and their setting trains; of a motor; a shaft driven by the motor; a dog to normally render the motor ineffective; manually-operable means to release the dog; an impulse wheel actuated by the shaft to repeatedly operate 60 a setting train; means controlled by the manually-operable means to arrest the impulse wheel after a predetermined stroke of the setting train; and a back-check pawl adapted to lock the impulse wheel against rotation in one direction to 65 permit restoration of the shaft while the impulse wheel remains stationary.

23. The combination with a carriage; and an escapement mechanism therefor; of a normally-restrained driver; a manipulative means to release the driver for operation; means to differentially arrest the driver; and escapement pawl oscillated by the driver; and tripping means actuated by the escapement pawl under control of 70 the arresting means to effect repeated oscillations

of the carriage escapement mechanism at a single operation of the manipulated means.

24. The combination with a normally idle series of stops, including a series of zero stops; indexing trains to set selected stops; and an escapement to control relative movement between the indexing trains and the stops, the indexing trains adapted to trip the escapement; of a key; and mechanism controlled thereby, upon a single operation of the key, to repeatedly operate one 10 of the indexing trains to automatically set a succession of similar stops.

25. The combination with normally idle stops, including zero stops; indexing trains to set selected stops; and an escapement to control relative movement between the indexing trains and the stops, the indexing trains adapted to trip the escapement; of a plurality of special keys; power means common to the special keys, and tripped by a single operation of any of such keys, to repeatedly 15 actuate one of the indexing trains; and arresting means individual to and controlled by the respective special keys to determine the number of times the indexing train shall be operated.

26. The combination with digit and zero indexing devices; setting trains appropriate thereto; and an escapement to effect relative movement between the indexing devices; and their setting trains; of a power-shaft; an impulse wheel releasably connected thereto for rotation in one direction therewith, and operable upon one of the setting trains to repeatedly actuate the train to cause it to successively set up a plurality of indexing devices; normally effective means to restrain the power-shaft and impulse wheel from 30 rotation in one direction; and manually operable means to trip the restraining means.

27. The combination with a plurality of differential elements; a plurality of denominational columns of stops to arrest the elements differentially; a denomination-selecting member; stop-setting trains positioned denominationally by the member; and keys to actuate the trains; of a set of auxiliary keys; a power device controlled by the keys to repeatedly actuate one of the stop-setting trains a different number of times depending on the particular auxiliary key depressed.

28. The combination with a plurality of differential elements; a plurality of denominational columns of stops to arrest the elements differentially; a denomination-selecting member; stop-setting trains positioned denominationally by the member; and keys to actuate the trains; of a set of auxiliary keys; a power device controlled by 50 the keys to repeatedly actuate one of the stop-setting trains a different number of times depending on the particular auxiliary key depressed and independently of the first-mentioned keys.

29. The combination with a series of differential elements; a series of columns of normally idle value and spacing stops for each element, to variously arrest the elements; an indexing train common to all stops of like value; and an indexing train common to the spacing stops; a denomination-selecting member to position the indexing trains in co-relation with the successive columns of stops; and keys to actuate the indexing trains; of means to automatically and 65 repeatedly actuate one of the indexing trains; and auxiliary keys to selectively determine when such means shall operate and the number of times the indexing train shall be operated.

30. In a machine of the class described, the 70 75

combination with a plurality of sets of indexing devices; key-operated indexing trains individual to the sets of indexing devices; and an escapement to effect relative movement between the sets of indexing devices and the indexing trains; of means to impart successive movement to one of the trains, including a normally ineffective, power-driven element; a member repeatedly reciprocated by the power-driven element to actuate one of the indexing trains; arresting means for the power-driven element; and a manipulative device to render the power-driven element and the arresting means effective, to determine the number of actuations imparted by the reciprocating member to the indexing train.

31. In a machine of the class described, the combination with a plurality of sets of indexing devices; key-operated indexing trains individual to the sets of indexing devices; and an escapement to effect relative movement between the sets of indexing devices and the indexing trains; of means to impart successive movement to one of the trains, including a normally ineffective power-driven shaft; a reciprocating member operable upon one of the indexing trains; means actuated by the shaft to reciprocate the member a plurality of times; arresting means for the power-driven shaft; and a manipulative device, which, at a single setting, renders the power-driven shaft at once effective, and controls the arresting means to become effective upon the completion of a predetermined number of reciprocations of the member.

32. In a machine of the class described, the combination with a plurality of sets of indexing devices; key-operated indexing trains individual to the sets of indexing devices; and an escapement to effect relative movement between the sets of indexing devices and the indexing trains; of means to impart successive movement to one of the trains, including a normally ineffective power-driven shaft; a reciprocating member operable upon one of the indexing trains; an actuating element journaled on the shaft, a clutch to connect the element to the shaft for rotation therewith in one direction; a reciprocating member for repeated operation by the actuating element, and effective to repeatedly operate one of the indexing trains; a manipulative device to render the power-driven shaft effective; arresting means for the actuating element conditioned by the manipulative device to become effective to arrest the actuating element upon the completion of a predetermined number of reciprocations of the indexing train; resetting means for the power-driven shaft; and means to lock the actuating element against movement with the shaft during the shaft-resetting operation.

33. In a machine of the class described, the combination with a plurality of sets of indexing devices; key-operated indexing trains individual to the sets of indexing devices; and an escapement to effect relative movement between the sets of indexing devices and the indexing trains; of means to impart successive movements to one of the trains, including a normally ineffective power-drive; an actuator operated by the power-drive in one direction; a reciprocating member operable upon one of the indexing trains under the influence of the actuator; spaced co-acting arresting elements for the actuator, one of which elements travels with the power-drive; and manually-operable means to co-act with the other of said co-acting arresting elements to con-

dition the element for arresting the co-acting element traveling with the power-drive.

34. In a machine of the class described, the combination with a plurality of sets of indexing devices; key-operated indexing trains individual to the sets of indexing devices; and an escapement to effect relative movement between the sets of indexing devices and the indexing trains; of means to impart successive movements to one of the trains, including a normally ineffective power-drive; means operable by the power-drive to repeatedly actuate one of the indexing trains; a plurality of manipulative devices to render the power-drive effective; a set of spaced co-acting stop members associated with each manipulative device, the spacing varying between the individual ones of each set of stop members, respectively; one of each set of stop members connected to travel with the power-drive, the co-acting stop member and the power-drive being adapted for relative movement; and means operable by the manipulative devices to condition the last-named stop members to arrest their co-acting stop members and the power-drive.

35. In a machine of the class described, the combination with a plurality of sets of indexing devices; key-operated indexing trains individual to the sets of indexing devices; and an escapement to effect relative movement between the sets of indexing devices and the indexing trains; of means to impart successive movements to one of the trains, including a normally ineffective power-drive; means operable by the power-drive to repeatedly actuate one of the indexing trains; a manipulative device to render the power-drive effective; spaced co-acting stop members, one of which is movable concomitantly with the power-drive, there being relative movement between the other co-acting stop member and the power-drive; and means operable by the manipulative device to condition the last-named stop member to arrest its co-acting stop member and the power-drive.

36. In a machine of the class described, the combination with a plurality of sets of indexing devices; key-operated indexing trains individual to the sets of indexing devices; and an escapement, to effect relative movement between the sets of indexing devices and the indexing trains; of means to impart successive movements to one of the trains, including a normally ineffective power-drive; means operable by the power-drive to repeatedly actuate one of the indexing trains; a manipulative device to render the power-drive effective; spaced co-acting stop members, one of which is movable concomitantly with the power-drive, there being relative movement between the other co-acting stop member and the power-drive; means operable by the manipulative devices to condition the last-mentioned stop member to arrest its co-acting stop member and the power-drive at the completion of a predetermined number of reciprocations of the indexing train; and flexible means to restore to its normal position that stop member relatively to which the power-drive is movable.

37. In a machine of the class described, the combination with a plurality of sets of indexing devices; key-operated indexing trains individual to the sets of indexing devices; and an escapement, to effect relative movement between the sets of indexing devices and the indexing trains; of means to impart successive movements to one of the trains, including a normally inef-

fective power-driven element; means operable by the power-driven element to repeatedly actuate an indexing train; arresting means for the power-drive, including a stop member operable 5 concomitantly with the power drive, and a co-acting stop member spaced from the first-named stop member with provisions for relative movement between it and the power-drive; manipulative means to render the power-drive effective, 10 and to condition the last-named stop member to arrest the first-named stop member at the completion of a predetermined number of operations of the indexing train; and a flexible link tensioned by the power-drive to return the second-

named stop member to normal position relatively to its co-operating stop member.

38. The combination with digit and zero indexing devices; setting trains therefor; and an escapement to effect relative movement between 5 the indexing devices and their setting trains; of a rotary, normally ineffective power-drive; means to release the power-drive for operation; manually conditioned means to arrest the power-drive in different angular positions during different operations; and means driven by the power-drive during such differential angular rotations, to impart corresponding pluralities of strokes to a setting train.

BURNHAM C. STICKNEY. 15
